UNITED STATES PATENT OFFICE

2,520,973

APPARATUS FOR FORMING AND DRIVING
STAPLES

Wendell L. Sorenson, Great Neck, N. Y.

Application August 6, 1947, Serial No. 766,506

1 Claim. (Cl. 1—2)

1

This invention relates to stapling or securing parts together, such as sheets of paper, card-board, fabrics and various other materials.

It is the usual practice in the stapling art to first form the staples and unite said staples to form a clip of staples. Then said clip of staples is mounted in a stapling apparatus which separates the leading staple from the clip, drives the separated staple into the material to be stapled and clenches the driven staple to the material to be stapled.

It is the principal object of the invention to overcome the disadvantage in the present method of stapling by eliminating the separate steps of forming staples and uniting said staples to form a staple clip and subsequently separating, driving and clenching a staple by simultaneously forming and driving a staple into the material to be stapled from a bar of severable and pliable material which takes the place of the staple clip in a stapling apparatus.

It is another object of the invention to form and drive staples from a bar of severable and pliable material wherein the form of staple is determined by the angle of severance or shear.

It is a further object of the invention to clinch staples formed from a bar with or without the use of an anvil.

Other objects and advantages of this invention will be described hereinafter.

In the drawing accompanying and forming a part of this application, there is shown apparatus for carrying out the present method of forming a staple from a bar of severable and pliable material and securing said staple in the material to be stapled and showing in Figure 1 a top plan view of a device for forming staples from a bar with an intermediate portion of said device broken away.

Figure 2 is a longitudinal sectional view taken on the line 2—2 of Figure 1 looking in the direction of the arrows.

Figure 3 is a fragmentary plan view, on an enlarged scale, with a guide plate and top member removed from the device to show a pair of clincher grooves.

Figure 4 is an end view of the device looking at the left hand side of Figure 2 with the guide plate removed from the device and showing a plunger in position prior to staple forming, driving and clinching position thereof.

Figure 5 is a view, on an enlarged scale, similar to Figure 4, and showing the plunger in its final position of clinching the formed staple to the material to be stapled.

2

Figure 6 is a fragmentary view showing a formed staple of ring shape secured to the material.

Figure 7 is an end view of the bar from which the staples are formed and showing a staple partially formed from said bar.

Figure 8 is a side elevational view of the bar with an intermediate portion thereof broken away and a staple partially formed at an end portion thereof.

Figure 9 is a perspective view of a staple formed from the bar before it is clenched to the material to be stapled.

In carrying out the method of simultaneously forming and driving a staple into the material to be stapled, there is provided a bar for severable and pliable material, such as sheet metal, and shown in the present illustration of the invention as comprising a V shaped bar of said material, as shown at 10.

The bar is slidably supported in a V shaped channel 11 corresponding in shape and of slightly larger dimensions than the dimensions of the bar to permit sliding movement of said bar in the channel. Said channel 11 is formed in two mating members 12 and 13 secured together by screws 14. The mating face of the member 12 is provided with a V shaped projection 15 extending on the longitudinal axis of said member and the mating face of the member 13 is arranged with a V shaped recess 16 of greater dimensions than the dimensions of the V shaped projection 15 to receive said projection and form therewith the channel 11.

One end of the member 12 is arranged with a vertical groove or channel 17 closed by a plate 18 secured to said end of the member 12 by screws 19. The closed groove 17 forms a slideway for a plunger 20 shown in the form of a thin cutting blade or cutter to sever a transverse end portion of the bar 10, form said severed portion into a staple and drive said formed staple into the material to be stapled, shown as two juxtaposed pieces of material at 21 in Figures 5 and 6. The plunger 20 may be manually or power driven as desired and yieldingly urged to the inoperative position shown in Figure 4 in the usual manner, not shown, as it does not constitute a part of the present invention. The lower end portion of the plate 18 is spaced laterally from the corresponding end of the member 13 whereby the plunger is guided to engage a transverse end portion of the bar projecting beyond the end of the member 13.

55 The end of the member 13 adjacent to the plate

18 is provided with a forwardly projecting shelf extending in spaced relation to the lower edge of the plate 18 and said shelf is formed by the forward end portion of a plate 22 secured in a recess 23 in the bottom face of the member 13 by screws 24, as shown in Figure 2. The member 13 is also arranged with an undercut portion 25 juxtaposed to the plate 22, as shown in Figure 2, to form a recess into which the material 21 is extended when supported by the shelf portion of the plate 22. The space between the lower end of the plunger guide plate 18 and the shelf portion of the plate 22 permits the engagement of the material on the shelf portion of the plate 22 in the path of movement of the plunger 20.

The forward end of the bar 10 is yieldingly urged against the lower end portion of the guide plate 18 in the path of movement of the plunger 20 by a spring 26 mounted in a recess 27 in the mating faces of the members 12 and 13 and compressed between the rear end of the bar 10 and closure plate 28 adjustably mounted on the member 12, as conventionally shown in Figure 2.

In the operation of the device illustrated, a staple is formed from the transverse end portion of the bar positioned in the path of travel of the plunger 20 by actuating said plunger into simultaneous engagement with the opposite edges of said transverse end portion of the bar 10 projecting beyond the front end of the member 13. Due to the direction of severance or shear being at an angle to the angle of projection of the side portions of the bar, the severed portions of the bar will curl in an outwardly and downwardly direction, as shown at 29 in Figure 7. By the use of the type of plunger shown, when the plunger 20 has completed its downward stroke and completely severed the severed bar portion from the bar, a staple of the shape shown at 30 in Figure 9 is formed.

The shearing or severing movement of the plunger 20 will simultaneously drive the ends 31 of the staple being formed into and through the material 21, and after said ends 31 have penetrated said material, they are clenched to the material, as shown at 32 in Figure 5, by clencher grooves 33 in the projecting shelf portion of the plate 22 constituting an anvil, as shown in Figure 3.

In Figure 6, there is shown a staple formed from the bar 10 and securing the material 21 in the shape of a ring 34 formed without the shelf 22 and the clencher grooves 33.

Having thus described my invention, I claim:

15 In an apparatus for forming and driving a staple, a support for a bar of severable material and of V shape in cross section, said support having a channel of corresponding V shape in cross section extending longitudinally through the support to rigidly support the bar with a portion of the bar extending from one end of the support, and a cutter reciprocating in a direction transversely of said end of the support and the extending portion of the bar with the opposite side edges of the bar facing the cutter whereby the cutter progressively severs said extending portion of the bar from the opposite side edges of the bar toward the longitudinal center of the bar and simultaneously curl the opposite severed 25 sections to progressive piercing and clinching positions.

WENDELL L. SORENSEN.
